INVENTOR:

JACOB BERNSTEIN,

BY

Jacob Bernstein & Son, Inc. ATTORNEYS.

UNITED STATES PATENT OFFICE.

JACOB BERNSTEIN, OF PHILADELPHIA, PENNSYLVANIA.

SKULL FOR ANIMALS' HEADS AND METHOD OF MAKING SAME.

Application filed November 5, 1927. Serial No. 231,238.

This invention, generally stated, relates to fur neck pieces and particularly the animal heads thereof, and relates more especially to an artificial skull for use in connection therewith.

The leading object of the present invention is to provide a new and novel method of making an artificial skull such as is used in connection with animal heads in fur scarfs, boas, fur neck pieces, and similar fur articles to provide a strong, inexpensive, and durable skull piece.

A further object of the present invention is to provide an article of the character above stated in which the artificial, animal-like skull piece is adapted particularly for attachment to the end of a boa or similar fur piece, and is so formed or simulated as to provide a simple, realistic, and rigid skull piece shaped from thin textile material impregnated with sizing material, as glue, such textile material comprising burlap, shoe-duck, buckramate, and the like.

A further object of the present invention is to provide an article of the character above stated in which there is applied to the sized textile material upon its underside a fibrous member, as card-board, for cooperatively receiving a conventional boa or neck piece clasp.

A still further object of the present invention is to provide a method of animal, artificial skull production in which in one operation a skull piece is automatically formed to provide a simple, rigid, and inexpensive skull part impregnated with adhesive material, as glue, whereby the skin of an animal fur-piece may be caused to adhere to the artificial skull part without the application of further adhesive.

A further object of the present invention is to provide a method of artificial skull formation for boa or neck piece use in which the skull part of sized burlap or the like has stapled with respect thereto and upon the underside thereof a fibrous, horizontally arranged piece of material, preferably card-board or the like.

Other and further objects not at this time more specifically referred to will be hereinafter set forth.

The invention consists of the novel construction hereinafter described and finally claimed.

The nature, characteristic features and

scope of the invention will be more fully understood from the following description taken in connection with the accompanying drawings forming part hereof, and in which:

Fig. 1, is a view in plan of a piece of sized 60 textile fabric in the original state before being introduced to the stamping process.

Fig. 2, is a view in plan showing the same piece of fabric as operated upon by a stamping machine.

Fig. 3, is a view in plan upon an enlarged scale illustrating the product shown in Fig. 2 with its surplus or excess material cut therefrom to provide the finished product, and in addition having stapled thereto the 70 fibrous sheet shown in Fig. 6.

Fig. 4, is a view in section taken upon the line 4—4 of Fig. 3.

Fig. 5, is a view in cross section taken upon the line 5—5 of Fig. 3.

Fig. 6, is a view of the underside of Fig. 3.

Fig. 7, is a view of a neck piece or boa the animal head of which is provided with a skull piece embodying the invention.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings, and referring more particularly to Figs. 1 and 2, at this time, I carry out my novel method of making animal artificial skulls by employing for the 95 purpose a blank of shoe-duck, burlap, buckramate, or the like, which is designated by reference numeral 1 in Fig. 1, which material may be of one, two or more plies, and is sized by the application thereto of an adhesive as glue or the like. In order properly to prepare the blank as thus formed, which may be of any length, for artificial skull formation, I introduce the blank to a suitable stamping machine. The blank 1 may be 100 moist, dry, cold, or in a heated condition when introduced to the stamping machine, and the stamping machine forms the article shown in Fig. 2, in which the reference numeral 2 designates the skull piece. The op-

erator now cuts away from the skull piece 2 the marginal excess parts 3, see Fig. 2, to provide the conformation shown in Figs. 3, 4, and 6. The next step in the operation 5 is to provide upon the underside of the skull part thus produced, which includes a nose piece 4, a plate of fibrous material, as card-board, which is designated by the reference numeral 5. This plate 5 is secured to the 10 nose piece 4 by means of staples 6 which may be introduced by any conventional form of stapling machine. The purpose of this plate 5 is to provide convenient means for accommodating a fur piece conventional 15 clamping member, not shown in the drawings, since the same forms no part of the present invention. The completed article, as above formed, is best seen in Figs. 3, 4, 5, and 6, and it is to be noted that the upper 20 skull portion is formed upon a pronounced arc of a circle, which is of rigid and firm construction. Further, the article is formed and sold as a single unit, and is of very light and durable construction, and may be 25 readily and cheaply made in two operations, namely: stamping of the burlap or other material employed, and stapling thereto the plate 5.

As previously referred to, the burlap is 30 impregnated with glue or other adhesive material so that when the animal head 7 of a fur neck piece 8 is fitted over the artificial skull, it being understood that there is sufficient moisture present either upon the fur 35 or the skull for causing adhesion, the fur piece can be readily secured to the artificial skull expeditiously without the application of additional adhesive properties, as is required where rubber, cork, or other conventional 40 artificial skulls are employed.

The plate 5 is so fitted to the underside of the nose piece 4 that the marginal edges of the plate serve to maintain the projected or nose parts of the skull in rigid, firm, and regular position. In the connection it is to 45 be noted that the plate 5 fits within the marginal edges of the projected nose piece. The staples 6 are longitudinally applied and substantially parallel the long, parallel edges of the nose part 4. 50

It will now be apparent that I have devised a novel and useful construction which embodies the features of advantage enumerated as desirable in the statement of the invention and the above description and 55 while I have in the present instance shown and described the preferred embodiment thereof which has been found in practice to give satisfactory and reliable results, it is to be understood that the same is susceptible 60 of modification in various particulars without departing from the spirit or scope of the invention or sacrificing any of its advantages.

Having thus described my invention, what 65 I claim as new, and desire to protect by Letters Patent, is:

As a new article of manufacture, an artificial skull comprising an integral member of fibrous material, as burlap, having projected therefrom a pointed nose part, a thin, flat card-board plate having a pointed end, said plate being horizontally arranged within the nose part only of said skull, and staples 70 securing said plate in position, said staples 75 being longitudinally disposed and substantially paralleling the longer edges of the nose part.

JACOB BERNSTEIN.
